UNITED STATES PATENT OFFICE.

GEORGE A. DELANO, OF ABRAMS, WISCONSIN.

SLIDING MOUTH-PIECE FOR HARMONICAS.

SPECIFICATION forming part of Letters Patent No. 375,608, dated December 27, 1887.

Application filed September 12, 1887. Serial No. 249,451. (No model.)

To all whom it may concern:

Be it known that I, GEORGE A. DELANO, a citizen of the United States, and a resident of Abrams, in the county of Oconto and State of Wisconsin, have invented certain new and useful Improvements in Sliding Mouth-Pieces for Harmonicas; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a harmonica, showing my sliding mouth-piece attached thereto. Fig. 2 is a longitudinal vertical sectional view of the same. Fig. 3 is a cross-sectional view on line $x-x$ in Fig. 2, and Fig. 4 is a bottom perspective view of the sliding mouth-piece removed from the harmonica.

My invention has relation to sliding mouth-pieces for harmonicas; and it consists in the improved construction and combination of parts of the same, as hereinafter more fully set forth.

In the accompanying drawings, the letter A denotes a harmonica of the usual construction, having an apertured plate, B, the apertures of which register with the perforations which conduct the breath to the free reeds of the harmonica.

C denotes the sliding mouth-piece, consisting of the casing, having its flat base provided with inwardly-bent flanges D D, which overlap and slide upon the parallel edges B' B' of the perforated plate, which extend slightly beyond the upper surface of the harmonica, and the upper portion of this mouth-piece is preferably curved and has apertures E' E² E³ located therein.

To the lower end of the mouth-piece is secured an apertured metallic strip, F, the apertures of which are adapted to register with the perforations in the plate secured to the harmonica when in operation.

J denotes an aperture in the side of the mouth-piece below the apertures in the edge of the same, which will be hereinafter more fully described. An inclined partition, K, extends downwardly from the aperture E' to the apertured strip, and a tube, L, extends downwardly from the aperture E' to the said

strip, thus forming three air-ducts, a b c, respectively, and through one of these ducts, c, the tune is played.

A transverse plate, M, is secured near the lower edge of the mouth-piece to the other side of the tune-duct, and has apertures N and O. A downwardly-opening valve, P, closes the aperture N, while an upwardly-opening valve, Q, covers the aperture O. These valves are secured to the opposite sides of the plate M, and are for the purpose of rendering complete octaves, as it is well known that in a harmonica an octave is four holes apart on the blow and five holes apart on the draw; hence the necessity of the oppositely-opening valves is readily seen without requiring further explanation.

The operation of my invention is as follows: The mouth-piece is first slid upon the perforated plate upon the harmonica, when it is ready for use. The tune or air is played through the main duct c by placing the mouth over the aperture E², and when it is desired to play a high octave at the same time the aperture E³, communicating with the air-duct d, having the oppositely-open valves, is also covered by the mouth, and the breath is forced to or the air drawn from the reeds of the harmonica. Again, should it be desired to make use of the diapason or play a chord which includes all the tones, the mouth-piece is so placed in the performer's mouth that all the apertures are covered, thus producing sweet and harmonious music, the aperture E' playing bass, while the aperture J, which communicates with three apertures, J' J² J³, in the metallic strip, plays tenor and alto. The said aperture J is well adapted for marking time by closing and opening it with the tongue.

It will be seen that my invention will cause the music to be played distinctly, and the notes, when desired, can be neatly cut off and are not jumbled together, as is the case when a mouth-piece is not employed, inasmuch as it is very difficult for a person to keep his mouth contracted so as to blow directly in one hole of the harmonica at a time; and the lips, which have heretofore been scratched and torn by sliding the mouth back and forth upon the upper portion of the harmonica, are now protected, as all it is necessary for the performer to do is to slide the harmonica back and forth,

while the mouth-piece is retained firmly in the mouth.

Having thus described my invention, I claim and desire to secure by Letters Patent of the 5 United States—

1. A sliding mouth-piece for harmonicas, consisting of a casing having a flat lower portion provided with inwardly-bent flanges, and an upper curved edge having apertures located 10 therein, a side aperture, a metallic apertured strip secured to the said flat portion above the flanges, and air-ducts extending entirely through said casing.

2. A sliding mouth-piece for harmonicas, 15 consisting of a casing having apertures in its upper edge, a side aperture, a flat lower portion having an apertured strip secured thereto, and air-ducts extending from the said apertures in the casing to the apertured strip.

20 3. A sliding mouth-piece for harmonicas, consisting of a casing having apertures located therein, substantially as herein described, an apertured metallic strip secured at the lower

end of said casing, air-ducts extending entirely through said casing, and an apertured plate 25 secured within said casing and having oppositely-opening valves.

4. The combination of a harmonica having an apertured plate, the parallel edges of which project beyond the upper surface of the harmonica, with a sliding mouth-piece consisting of a casing having a flat lower portion provided with inwardly-bent flanges, and an upper curved edge having apertures located therein, 30 a side aperture, a metallic apertured strip secured to the said flat portion above the flanges, and air-ducts extending entirely through said casing.

In testimony that I claim the foregoing as my own I have hereunto affixed my signature in 40 presence of two witnesses.

GEORGE A. DELANO.
